UNITED STATES PATENT OFFICE.

HELEN P. JOHNSTONE, OF GLEN RIDGE, NEW JERSEY, ASSIGNOR TO
CHENEY BROTHERS, OF MANCHESTER, CONNECTICUT.

DESIGN FOR TEXTILE FABRIC.

SPECIFICATION forming part of Design No. 31,457, dated August 22, 1899.

Application filed June 3, 1899. Serial No. 719,317. Term of patent 3½ years.

To all whom it may concern:

Be it known that I, HELEN P. JOHNSTONE, of Glen Ridge, in the county of Essex and State of New Jersey, have invented and produced a new and original Design for Textile Fabrics, of which the following is a specification, reference being had to the accompanying drawing, forming a part thereof.

My invention relates to a design to be wrought into a fabric or printed or displayed upon the surface of such fabric that may be used for hangings, draperies, furniture-coverings, or even dress goods or the like, and the said design may be produced in such colors as may be desired.

My invention consists in the pictorial representation in conventional form of symbols directly relating to the old Egyptian civiliza-

tion—the lotus-blossom, scarabeus, the asp, and the hawk-headed god, together with the spread wings of the scarabeus, all conventionally treated and grouped to comprise the design as herein pictorially shown.

The accompanying drawing is a plan view of a piece of printed fabric showing a repeat of my design.

What I claim as new, and desire to secure by Letters Patent, is—

The design for a textile fabric as herein described and shown in the accompanying drawing.

HELEN P. JOHNSTONE.
